CLAIM

The ornamental design for a kitchen and bathroom storage set, as shown and described.

DESCRIPTION

FIG. 1 is a front perspective view of a kitchen and bathroom storage set, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of component one shown separated from the other components;

FIG. 10 is a front perspective view of component two shown separated from the other components;

FIG. 11 is a front perspective view of component three shown separated from the other components;

FIG. 12 is a front perspective view of component four shown separated from the other components;

FIG. 13 is a front view thereof;

FIG. 14 is a left side view thereof;

FIG. 15 is a top view thereof;

FIG. 16 is a front perspective view of component five shown separated from the other components;

FIG. 17 is a front view thereof;

FIG. 18 is a left side view thereof; and,

FIG. 19 is a top view thereof.

The broken lines in the drawings are for the purpose of illustrating environment and form no part of the claimed design.
